CLAIM

The ornamental design for a eave track, as shown and described.

DESCRIPTION

FIG. 1 is a front perspective view of an eave track showing my new design.

FIG. 2 is a back perspective view thereof.

FIG. 3 is a front view thereof.

FIG. 4 is a back view thereof.

FIG. 5 is a top view thereof.

FIG. 6 is a bottom view thereof.

FIG. 7 is a left side elevation view thereof; and,

FIG. 8 is a right side elevation view thereof.

The broken lines in the drawings represent portions of the eave track and form no part of the claimed design.
